UNITED STATES PATENT OFFICE.

ALFRED CLEMENT STEWART, OF SANTA PAULA, CALIFORNIA.

MOTOR-CARRIAGE.

SPECIFICATION forming part of Letters Patent No. 633,666, dated September 26, 1899.

Application filed March 17, 1898. Serial No. 674,257. (No model.)

To all whom it may concern:

Be it known that I, ALFRED CLEMENT STEWART, a citizen of the United States, residing at Santa Paula, in the county of Ventura and State of California, have invented a new and Improved Motor-Carriage, of which the following is a full, clear, and exact description.

One object of my invention is to provide a motor-carriage of superior strength and lightness and to so support the motor that injury thereto by jar is reduced to the minimum. This is accomplished by flexibly and yieldingly connecting the motor-frame with the carriage-body or frame and confining such movement within certain limits.

Another object is to provide simple and convenient means for increasing or diminishing the speed and starting and stopping the motor-carriage.

My invention relates to that class of motor-carriages having a motor-carrying frame journaled at one end on the axle of the driving-wheels and with the other end supported by springs. Preferably the motor is mounted at the spring-supported end of said frame and as close thereto as is practicable, so that the weight of the motor is carried by the springs rather than immediately by the axle. The springs may be supported by a frame which connects the axles or may be supported by the axles directly, and in such case the springs of the carriage-body are utilized for supporting the motor. In carriages of this class the motor adds so much to the weight that must be carried at all times in addition to the load that when the driven wheels or those which are not directly acted upon by the motor strike an obstruction they will not readily pass over it, but will have a tendency to stop until they are forced forward by the onward movement of the carriage. The strain caused by this hesitation or temporary stoppage of the driven wheels tends to racking the vehicle. In my newly-invented vehicle the two axles are connected together by a rigid frame independent of the connection through the body and the springs, thus to withstand said strain. If the rigid connection were omitted, the entire strain of forcing the driven wheels over obstructions would have to be borne by the other connections, and the result would be that the carriage would be racked to pieces

quicker than when the extra rigid connection is used.

My invention includes features of construction herein described and claimed.

I propose to apply power to the driving-wheels through the medium of friction-gear, and my invention includes the combination, with the driving-disk of the gear, of a lever and connections for shifting the friction-disk shaft endwise to throw it into and out of gear with the driving-disk and yielding means for normally holding the lever in position to cause the disks to engage each other with the pressure normally required for driving the friction-disk.

The accompanying drawings illustrate my invention.

Figure 1 is a side elevation of a motor-carriage provided with my invention. Fig 2 is a fragmental plan section of the same. Line 2, Fig. 1, indicates the line of section.

A A' indicate two wheel-carried axles, one, A, being provided with driving-wheels B B'. C indicates the frame connecting said axles.

D indicates the spring-carried frame, which serves as the carriage-body of the vehicle. This frame is mounted on springs E E', carried by said axles.

F indicates a friction-disk carried by a frame G. Suitable means are provided for connecting the disk with the driving-wheels A A' for driving the same.

G indicates a motor-carrying frame having one end journaled on the axle by any suitable means—such, for instance, as the tube g, with cups g', cones a" being mounted on the axle and balls a between the cups and cones. The other end of the frame G is swung from the carriage-body by means of a centrally-arranged link g'', a spring g''' being interposed between the carriage-body or frame D and the motor-frame G to take up the lost motion of the link to virtually prevent vertical movement of the end of the frame G with relation to the spring-carried frame D.

It is a well-known fact that to secure the greatest comfort in riding-vehicles it is necessary to permit of a certain amount of movement of the body backward and forward to avoid the jar that would be occasioned by the temporary retardation and acceleration of the wheels in passing over obstructions or

uneven surfaces in the road. To secure this desirable feature in my carriage, in which the motor is prevented from this backward and forward movement (except in unison with the 5 wheels) on account of its frame being secured at its rear end to the axle, I use the flexible connection or link g'' , which while it supports the front end of the motor-frame does not prevent the independent backward and forward 10 movement of the body; but as this link permits a greater or less degree of vertical movement of the front end of the motor-frame independently of the movement of the body, which would jar the machinery to a greater or less 15 extent if not controlled or counteracted, the spring g'' is rendered a compression-spring by placing its ends one against the body and the other against the motor-frame. In this manner it will have a tendency to keep the link 20 connection taut and prevent any sudden jar to the motor which might occur if the motor-frame could move vertically independently of the carriage-body, even to the slight extent of the lost motion occasioned by the link connection. By placing the spring around the 25 link it will be retained in position without need of other fastening. This construction gives a very strong and simple connection between the body and the motor-frame; as the 30 link supports the front end of the frame and the greater portion of the weight of the motor and also limits the distance to which the front end of the frame and the body can be separated, while the spring graduates—*i. e.*, 35 modifies by degrees—the distance to which they may approach each other.

H indicates a motor mounted on the motor-frame G .

I indicates a driving-disk carried by the 40 motor-frame and driven by the motor through suitable mechanism and engaging the friction-disk F to drive it.

J indicates a screw-threaded sleeve carried by the frame G . K indicates a screw-threaded 45 box screwed into such sleeve.

L indicates a shaft journaled in and carried by the box K and connected with the driving-wheels by suitable means, such as the pinion M and driving spur-gear N and the equalizing 50 mechanism $O P Q Q'$. This mechanism being of the ordinary form, description thereof is unnecessary herein.

Suitable means are provided for turning the sleeve-box K to shift the shaft L endwise 55 to bring the disk F into engagement with and to withdraw it from the driving-disk I . For this purpose R indicates a lever for turning the box to screw and unscrew the same into and out of the sleeve J . The screw-threads 60 are square and of coarse pitch, so that a comparatively small movement of the lever will give sufficient end motion to the box and shaft L . Yielding means are provided for normally holding the lever in position to cause the disks 65 to engage each other with the pressure normally required for driving the friction-disk

F. In the drawings I have shown a spring S for this purpose.

T indicates a hand-lever connected with the lever R by connecting-rod t , and U indicates a notched segment for holding the lever T . 70

The driving-disk I is fastened to a sleeve T , which is slidably mounted on the motor-shaft h' and is held from turning thereon by a spline h and a feather i .

V indicates a hand-lever fastened to a rock-shaft W on the inside of the carriage, connected with a sliding box X , which is journaled on the sleeve I , which carries the driving-disk I . By operating the lever V the driving-disk I will be moved across the face of the friction-disk F , thus increasing and diminishing the speed at which the disk F will be driven by the disk I at a given speed of the motor, and thus to increase or diminish the speed of the motor-carriage without changing the speed of the motor. 80

Since the disk F is movable toward and from the disk I , it may be moved away from the disk I until the latter has been moved 90 upon its shaft and placed where desired, when the disk F may be moved back into engagement with the disk I . This avoids moving the disk I laterally across the face of the disk F when they are in contact with each other, 95 as when the engine and carriage are both standing still. It also permits of the instant separation of the motive power from the carriage—as, for instance, in order to stop the carriage suddenly—and it would be impossible to wait for the fly-wheel of the motor to come to a standstill. 100

Now, having described my invention, what I claim as new, and desire to secure by Letters Patent, is—

1. A motor-carriage having a motor-carrying frame journaled at one end on the axle of the driving-wheels and with the other end supported by a link connected with a frame or carriage-body which is mounted on springs 110 carried by the axles of the carriage; and a compression-spring between the spring-carried frame or carriage-body and the link-carried end of the motor-frame to take up the lost motion of said link. 115

2. The combination of the wheel-carried axles; driving-wheels being on one of said axles; a frame connecting said axles; a frame journaled at one end to the axle of the driving-wheels and being spring-supported at the 120 other end; a screw-threaded sleeve carried by such frame; a screw-threaded box screwed into such sleeve; a shaft journaled in and carried by the box and connected with the driving-wheels to drive them; a friction-disk 125 fixed on said shaft to drive it; a driving-disk to engage the face of the friction-disk to drive it; and means for turning the box to shift the shaft endwise.

3. The combination of the wheel-carried 130 axles; driving-wheels being on one of said axles; a frame connecting said axles; a frame

journalized at one end to the axle of the driving-wheels and being spring-supported at the other end; a screw-threaded sleeve carried by such frame; a screw-threaded box screwed into such sleeve; a shaft journalized in and carried by the box and connected with the driving-wheels to drive them; a friction-disk fixed on said shaft to drive it; a driving-disk to engage the face of the friction-disk to drive it; a lever for turning the box to shift the shaft endwise; and yielding means for normally holding the lever in position to cause the disks to engage each other with the pressure normally required for driving the friction-disk.

4. In a motor-carriage the combination of the wheel-carried axles; driving-wheels being on one of said axles; a frame connecting said axles; a motor-carrying frame rigidly journalized at one end to the axle of the driving-wheels and being spring-supported at the other end; a friction-disk carried by such frame and connected with the driving-wheels to drive them; a driving-disk shaft mounted on said motor-carrying frame; a motor on such frame and connected with said shaft; a driving-disk mounted on said shaft to turn

therewith and to slide therealong and arranged to engage the face of the friction-disk to drive it; and means for sliding the driving-disk along its shaft and holding it in different positions thereon. 3c

5. In a motor-carriage, the combination with a friction-gear, of a lever and connections for shifting the friction-disk shaft endwise to throw the disks into and out of gear; and yielding means for normally holding the lever in position to cause the disks to engage each other with the pressure normally required for driving the friction-disk. 4c

6. In a motor-carriage, the combination, with the wheeled axles and the body; of a motor-frame supported thereby; a motor on the frame provided with a shaft; a driving-disk slidingly mounted on the shaft; a driven disk arranged with its face parallel with said shaft, and movable at right angles toward and from the same; and levers for moving each of said disks independently of the other. 45

ALFRED CLEMENT STEWART.

W. J. TRAVERS.

It is hereby certified that in Letters Patent No. 633,666, granted September 26, 1899, upon the application of Alfred Clement Stewart, of Santa Paula, California, for an improvement in "Motor-Carriages," errors appear in the printed specification requiring correction, as follows: On page 3, line 18, after the word "frame" the word *rigidly* should be inserted and same page, line 19, after the word "frame" the word "rigidly" should be stricken out; and that the said Letters Patent should be read with these corrections therein that the same may conform to the record of the case in the Patent Office.

Signed, countersigned, and sealed this 17th day of October, A. D., 1899.
